UNITED STATES PATENT OFFICE.

ALAN STEWART FITZGERALD, OF LONDON, ENGLAND, ASSIGNOR TO GENERAL ELECTRIC COMPANY, A CORPORATION OF NEW YORK.

PROTECTIVE SYSTEM.

Application filed August 13, 1924. Serial No. 731,867.

To all whom it may concern:

Be it known that I, ALAN STEWART FITZGERALD, a subject of the British Empire, residing at London, England, have invented 5 certain new and useful Improvements in Protective Systems, of which the following is a specification.

My invention relates to improvements in protective systems for alternating electric 10 current circuits, machines and apparatus and more particularly to the current transformers used in protective systems of the circulating current type, and an object of my invention is to provide a protective system having 15 improved operating characteristics.

Current transformers for use in connection with high tension circuits, especially the kind known as bushing transformers, are inefficient in comparison with low tension current 20 transformers, owing to the greater space occupied by the primary insulation of the former. The current output from a high tension current transformer, moreover, is small in comparison with that from a low 25 tension current transformer owing to the fewer primary ampere turns of the former (assuming a single primary turn in each). Owing to these facts, difficulty has been experienced in accurately balancing, over a 30 wide range of primary load, the secondary currents of current transformers in circulating current protective systems for protecting circuits of different potentials or the current transformers of which have different 35 characteristics. An object of my invention is to provide means for overcoming this difficulty. It is, therefore, especially applicable to systems and apparatus arranged for the protection of a transformer, or of a pair of 40 parallel feeders at different potentials.

According to my invention, the combined effect of the series connected secondary windings of two current transformers upon an additional secondary winding of one of the 45 current transformers is neutralized by the primary winding thereof, when the primary currents are of normal values, that is, when there is no fault in the circuit that is being protected. The additional secondary winding 50 is connected to a tripping device or protective relay and serves to operate the same in the event of the normal relationship between the currents of the primary conductors being disturbed, such as may be caused by 55 a fault.

My invention will be better understood from the following description taken in connection with the accompanying drawing and its scope will be pointed out in the appended claims.

In the accompanying drawing, Fig. 1. represents a simple arrangement of circulating current protection according to prior practice, and Fig. 2 an arrangement embodying 65 my invention.

Like reference numerals are used whenever possible to denote similar parts and in Fig. 1 the cores 10, 11 surround the high tension primary 12 and the lower tension primary 13 respectively. The secondary 70 windings, 14 and 15 respectively, are connected for circulating current, a protective relay 16 being arranged across equi-potential points to operate in a manner well understood.

In Fig. 2 two secondary windings 14, 14' are provided upon the core of the current transformer which has the poorer characteristic, that is upon the core 10 of the current transformer associated with the higher 80 potential primary 12. There is usually ample space on a bushing transformer for this purpose. The secondary winding 14 of the double-wound current transformer is connected with the secondary winding 15 of the 85 other current transformer in such sense and is so arranged that current induced in the latter winding and flowing through the former will produce in the core 10 of the double-wound current transformer a mag- 90 netic flux equal and opposite to that produced therein by the primary winding 12 thereof, when conditions in the circuit that is being protected are normal. In these circumstances the resultant flux in the core 10 95 of the double-wound current transformer is substantially zero since the magnetomotive force in the core 10 due to the series connected secondary windings 14 and 15 is neutralized by the magnetomotive force of 100 the primary winding 12. The other or additional secondary winding 14' is connected to a tripping device or protective relay 16 and will be energized only when the normal 105 relation in the protected circuit is disturbed. When it is so energized, it may operate to open the main protected circuit, to give a warning signal, or in any other desired manner. Owing to the relatively large current output from the current transformer asso- 110

ciated with the circuit of the lower potential, there is no difficulty in maintaining the desired ratio of ampere turns between the series connected secondary windings 14 and 15.

In some cases it may be necessary to introduce a restraining bias in a manner that is well known. The impedance representing the restraining winding may then be excited from a winding on the core of the current transformer which does not carry the additional winding, that is, on the core 11 of the current transformer associated with primary 13. Preferably it is connected in the circuit of the series-connected windings 14, 15.

If at a given instant the currents in the primary windings 12 and 13 are flowing in the directions indicated by the arrows 17, then the directions of currents in the secondary windings 14 and 15 are indicated by the arrows 18 in normal conditions. A consideration of the windings 12 and 14 in Fig. 2 will show that they produce fluxes in the core 10 in opposite senses. Consequently, under normal conditions, that is, the desired current balance in the conductors 12 and 13, substantially no current flows in the auxiliary secondary winding 14' and the relay 16 is not operated. Upon an unbalance in the currents in the conductors 12 and 13, however, the resultant flux in the core 10 will not be zero and current will flow in the secondary winding 14'. This current, depending upon the degree of unbalance for which the relay 16 is set to operate, will actuate the relay.

What I claim as new and desire to secure by Letters Patent of the United States, is:

40 1. A protective arrangement for an alternating electric current circuit wherein two current transformers have their primary

windings connected in said circuit and their secondary windings connected in series, characterized by the fact that one of said transformers is provided with an additional secondary winding arranged so that the combined effect thereon of said series connected secondary windings is neutralized by the primary winding of said one transformer when circuit conditions are normal.

2. A protective arrangement for an alternating electric current circuit comprising two current transformers having primary windings connected in said circuit and secondary windings connected in series, an auxiliary secondary winding on one of said transformers and a relay connected in circuit with said auxiliary winding, the connection and arrangement of said secondary windings being such that under normal conditions on said circuit the combined effect of said series connected secondary windings is neutralized by the primary winding of said one transformer.

3. A protective arrangement for a pair of conductors carrying alternating electric currents at different potentials comprising a magnetic core around each conductor, a winding on each of said cores, said windings being connected and arranged to produce under normal conditions on said conductors a magnetomotive force in the core around the conductor at the higher potential neutralized by the magnetomotive force due to the current in the higher potential conductor whereby the resultant flux in the core is normally substantially zero, an auxiliary winding on the core of the higher potential conductor, and a relay connected in circuit with said auxiliary winding.

In witness whereof, I have hereunto set my hand this thirtieth day of July 1924.

ALAN STEWART FITZGERALD.
